(57) **CLAIM**

The ornamental design for dog training device, as shown and described.

DESCRIPTION

FIG. 1 is a perspective view of a dog training device showing my new design;
FIG. 2 is another perspective view thereof;
FIG. 3 is a front view thereof;
FIG. 4 is a rear view thereof;
FIG. 5 is a left side view thereof;
FIG. 6 is a right side view thereof;
FIG. 7 is a top plan view thereof;
FIG. 8 is a bottom plan view thereof;
FIG. 9 is an enlarged view of portion B shown in FIG. 2; and,
FIG. 10 is an enlarged view of portion A shown in FIG. 1. The broken lines depict portions of the dog training device that form no part of the claimed design.
